UNITED STATES PATENT OFFICE.

JOSEPH J. COHN, OF NEW YORK, N. Y.

DESIGN FOR AN AUTOMOBILE-HORN.

43,735.

Specification for Design.

Patented Mar. 25, 1913.

Application filed November 8, 1909. Serial No. 526,941. Term of patent 7 years.

To all whom it may concern:

Be it known that I, JOSEPH J. COHN, a citizen of the United States, residing in the borough of Manhattan, in the city, county, and State of New York, have invented a certain new, original, and ornamental Design for Automobile-Horns, of which the following is a specification, reference being had therein to the accompanying drawings, forming a part thereof.

Referring to the accompanying drawings,

Figure 1 is a front view of an automobile horn showing my new design, and Fig. 2 is a side view thereof.

I claim—

The ornamental design for an automobile horn, as shown.

JOSEPH J. COHN.

Witnesses:

P. V. WENING,

P. FRANK SONNEK.
